UNITED STATES PATENT OFFICE

2,305,787

INTERNAL COMBUSTION ENGINE

Josef Kales, Stuttgart, Germany; vested in the
Alien Property CustodianApplication September 15, 1938, Serial No. 230,013
In Germany September 18, 1937

3 Claims. (Cl. 123—90)

This invention relates to internal combustion engines and has for an object the provision of means whereby the valve operating time may be changed as by a movement of the valve operating shaft relative to the crank shaft.

Another object of the invention is to provide such a phase changing device which may be adjusted while the engine is operating.

Another object is to provide such a device actuated by hydraulic, pneumatic, or other power means.

Another object is to provide such a phase changing device operated by lubricant pumped by the usual lubricating pump of the engine or by the usual air pressure pump which provides compressed air for braking.

Another object is to provide such a lubricant operated device so constructed that the minimum pressure necessary for proper lubrication is available independent of the demands of said phase changing device.

Another object is to provide such a device, the setting of which is influenced by the rotation speed of the internal combustion engine as by the use of a centrifugal governor, a pump, an electric generator, or by the vacuum in the intake passage, so that the adjustment of the phase changing device will take place automatically in accordance with the conditions of operation of the engine.

Another object is to provide such a device in which not only the setting in one direction but also the return setting is accomplished by power means.

Further objects and advantages of this invention will be apparent from consideration of the specification as illustrated by the accompanying drawings of possible embodiments of the invention, in which drawings:

Fig. 1 illustrates more or less schematically a device making use of the invention, certain parts thereof being shown in cross-section, the phase changing mechanism being shown operated by a special pump;

Fig. 2 illustrates a modified form in which the usual lubricant pump of the engine is utilized to operate the valve timing and in which the device is influenced by a centrifugal governor adjusting means;

Fig. 3 illustrates a further modification showing a double acting adjusting means wherein setting in both directions is accomplished by fluid pressure; and

Fig. 4 is an enlarged detail view of a part of the form illustrated in Fig. 3.

Referring to the form illustrated in Fig. 1, the internal combustion engine is designated as 1; 2 its carburetor whose throttle vane 3 is actuated by the link rod 4 operated by the fuel controlling foot pedal 5. The driving of the control shaft 6, which may be the valve cam shaft, is brought about from the crank shaft 7 through the gear wheels 8, 9, the splined shaft 10, and the beveled gear pair 11 and 12. The two parts of the splined shaft 10 are coupled with one another through the adjustable sleeve member 13 in such a manner for example that it interengages in its lower part with straight splines and in its upper part with helical splines so that when sleeve 13 is shifted the phase relationship between shafts 7 and 6 will be altered.

A gear pump driven by the motor 14 is designated as 14. Its pressure side D is connected through conduit 17 with the cylinder space 15 containing the adjustable piston 16. The pressure side D of the pump 14 is connected with its suction side S through a conduit 18 into which the valve piston 19 with its specially formed controlling edges 20 is inserted. The valve piston 19 is coupled with the fuel control lever 5 by means of a link 21. A relief valve 22 is inserted in parallel with the pump 14. The adjusting piston 16 works against the pressure of a spring 23 and adjusts the adjusting member 13 by means of the piston rod 24 and the lever 25.

The arrangement, according to this invention, operates in such a manner that starting at idling speed, upon operation of the fuel control lever 5 the controlling edges 20 of the valve piston 19 gradually shuts off the fluid circuit through the conductors 17 and 18, which up to now formed a short circuit, so that the pressure from the pressure side D of the pump 14 now increases. With it also, however, the pressure in the cylinder space 15 rises so that the piston 16 is gradually raised and so adjusts the adjusting member 13 through the piston rod 24 and the lever 25, that the valve openings are advanced relative to the piston position until the forces acting upon the piston are in equilibrium. If reversely, the driving medium supply is lessened, i. e., the valve piston is drawn toward the right, the pressure is reduced and the cam shaft is displaced reversely.

In the example shown in Fig. 2, the supply of the pressure medium is maintained by the usual lubricating oil pump 26 whose pressure side D supplies the lubricating points 28 and 29 by means of the conduit 27; 30 indicates a pressure limiting valve which determines the pressure neces-

sary for the correct lubrication of the bearing. From the pressure side D, a conduit 31 also leads to the cylinder space 32 within which is slidably mounted the piston 33 which is connected with the adjustable member 13. In the conduit 31 an adjustable throttle 34 is inserted after which a conduit 35 branches off which leads to the valve cylinder 36 in which the slotted valve slide 37 is located. From the valve cylinder 36 the conduit 38 leads to the suction side S of the pump 26 as well as to the sump 39. The valve slide 37 is connected with the adjusting sleeve of the centrifugal governor 42 by means of the link 40 acting through lever 41. The centrifugal governor has such a characteristic that in the case of increased speed, the valve slide 37 cuts off the flow of oil through the conduit 35 at first swiftly and then increasingly slower. A throttling valve inserted in the conduit 27 is designated as 43 which permits the maintenance of the pressure for the actuation of the adjusting drive substantially higher than the pressure necessary for lubrication.

The arrangement according to Fig. 2 operates in such a manner that during idling the valve slide 37 opens up the oil path through the conduit 35; the throttling valve 34 in this case determines substantially the amount of pressure acting for the lubrication of the bearings 28 and 29 and is also to be so adjusted that the minimum pressure necessary for such lubrication is assured. The pressure existing in the cylinder space 32 is, during idling, small for this adjustment, so that the adjusting member 13 is not moved from its upper position. If now the supply of fuel to the internal combustion engine is increased, the engine and the centrifugal governor 42 connected therewith increases in speed. The valve slide 37 is drawn to the right so that it quickly cuts off the flow of oil through the conduit 35. The pressure increases substantially and through the conduit 31 presses the piston 33 of the adjusting drive downwardly, and so adjusts the control shaft a substantial amount. If the engine continues to accelerate, the distance moved by the valve piston 37 gradually becomes less, due to the particular characteristics of the centrifugal governor, resulting in gradually smaller adjustments of the valve cam shaft which is also desirable for securing best fuel economy. In the case of a decreasing of the driving medium, the speed of the engine is decreased and therewith also the pressure in the cylinder space 32 decreases, slightly at first. The valve cam shaft will also now be adjusted a slight amount until from approximately double idling speed it falls off rapidly and then quickly positioned for idling speed.

In the example according to Fig. 3, the adjusting member 13 is connected by means of a ball bearing 44 with a double acting annular piston whose upper side is designated as 45 and its lower side as 46. The piston is maintained against rotation and has a sealing relationship inwardly against inwardly directed extensions 47 or 48 of the upper and lower pressure spaces 49 and 50 respectively. The upper pressure space 49 is connected to the valve cylinder 53 by means of the conduit 51, the lower pressure space by means of the conduit 52. Cylinder 53 contains a valve piston 59 whose reduced central part is connected with the pressure side D of the gear wheel pump 55 by means of the conduit 54 and whose outer sides 56 and 57 lead to the suction side S of the

75 pump 55 through the conduit 58. The valve piston 59 is linked to the bar 61 by means of the rod 60, the left end of bar 61 being connected with the downwardly extending restoring rod 62 and its right end is connected at the hinge 63 with the actuating bar 64. The downwardly extending restoring rod 62 is rotatably connected at its upper end with the upper part 78 of the adjusting member 13. The hinge 63 is journaled 80 between the adjustable abutments 65 and 66, whereas the outer pivotal point 67 is adjustably positioned. At the point 68 is attached the pivotal rod 69 upon which operates the piston 71 located in cylinder space 72 which is connected through the conduit 73 with the intake manifold 74 of the internal combustion engine 1.

In Figs. 3 and 4, which represent full load position, the adjusting member 13 and the adjusting pistons 44 and 46 are shown in their uppermost position which corresponds to the greatest advance of the valve cam shaft 6, the valve piston 59 being in its central position.

If now the drive medium supply to the motor is decreased, that is, the throttling vane 3 is partially closed, the vacuum in the suction tube 74 and thereby in the cylinder space 72, will be increased so that the piston 71 rises. The actuating rod 64 swings about the pivotal point 67 in a clockwise manner and carries with it the bar 61 by means of the hinge pivot 63, which by means of the pivoted rod 68, raises the control piston 59. Thereby, the fluid located in the lower pressure space 58 escapes through the conduit 52, the outer side 57 of the control cylinder, and the conduit 58, to the suction side S, and at the same time pressure fluid is delivered to the upper pressure space 49 of the adjustable drive cylinder through the conduit 51; the pistons 45 and 46 are thus pressed downwardly and through the bearing 44 move the adjusting member 13 which adjusts the two parts of the splined shaft 10 relative to one another by means of the screw operation so that now a less advance of the cam shafts corresponds to a lower power delivery. Upon the lowering of the adjusting member 13, however, the downwardly extending restoring rod 62 is also moved and moves the pivotal rod 61 about the pivotal point 63 in such a manner that the control piston 59 is gradually restored to central position closing the canals leading to the conduits 51 and 52. Through the arrangement and formation of the linkage and the drive acted upon by the control piston, the desired relationship between the cam shaft adjustment and the intake manifold vacuum can be produced so that for any partial load there corresponds a wholly predetermined position of the adjusting member. In other words, it is hereby brought about that the valve times of the motor can be made to correspond to the current load condition with sufficient exactness whereby a certain fine adjustment can be brought about through the adjustments of the abutments 65 and 66 and of the pivotal point 67.

The invention makes it possible not only to adjust the cam shaft without requiring much power on the part of the operator but furthermore provides the means which can be used for the automatic adjustment of the same. Through the special formation of the controlling edges of the valve piston or of the valve cylinder and the member influenced by it, an adaptation of the valve operating times for every partial load is hereby brought about in such a manner that, for

example, for the entire range of speed the best utilization of fuel, the highest power, or the highest torque may be achieved.

This invention extends to internal combustion engines of all types whether of the carburetor type or with fuel injection, whether the cylinders are positioned in one or several rows, or radially, or whether, furthermore, the valving of the internal combustion engine is brought about by means of valves or by means of slides. Furthermore, it is immaterial how the adjusting drive and the pressure producer which delivers the pressure medium is formed and positioned and how, furthermore, the pressure producer is connected with its branches. Furthermore, it is without importance what type of pressure medium is used, for example, whether it be oil, and particularly lubricating oil, or oil used for fluid brakes, or air.

It will be noted that the constructions shown and described will serve admirably to accomplish the objects stated above. It is to be understood, however, that the constructions disclosed above are intended merely as illustrative of the invention and not as limiting as various modifications therein may be made without departing from the invention as defined by a proper interpretation of the claims which follow.

I claim:

1. In an internal combustion engine, a power shaft, valves, means connected between said power shaft and said valves for operating said valves, said means including a phase changing device and a fluid operated power device for operating said phase changing device, a source of fluid under pressure, a valve for controlling the

flow of said fluid to said phase changing device, fuel supply controlling means, manual adjusting means therefor, and means for controlling said valve also actuated by said manual means.

2. In an internal combustion engine having a carburetor and a throttle, a power shaft, valves for said engine, valve operating means including a cam shaft, means connected between said power shaft and said cam shaft for operating said cam shaft, said means including a device for changing the rotative phase relationship between the power shaft and the cam shaft, and a fluid operated power device for operating said phase changing device, a source of fluid under pressure, a valve for controlling the flow of said fluid to said phase changing device, and means for controlling said valve in accordance with the position of the throttle whereby the phase relationship between the cam shaft and the power shaft is controlled by the load upon the engine.

3. In an internal combustion engine having a carburetor and a throttle, a power shaft, valves for said engine, valve operating means including a cam shaft, means connected between said power shaft and said cam shaft for operating said cam shaft, said means including a device for changing the rotative phase relationship between the power shaft and the cam shaft, and a fluid operated power device for operating said phase changing device, a source of fluid under pressure, a valve for controlling the flow of said fluid to said phase changing device, and common means for controlling the position of said throttle and said fluid controlling valve.

JOSEF KALES.
